UNITED STATES PATENT OFFICE.

JASPER JOHNSON, OF GENESEO, NEW YORK.

VICE.

Specification of Letters Patent No. 13,681, dated October 16, 1855.

To all whom it may concern:

Be it known that I, JASPER JOHNSON, of Geneseo, in the county of Livingston and State of New York, have invented a new and 5 useful Improvement in Vises; and I do hereby declare that the following is a full, clear, and exact description of the construction and operation of the same, reference being had to the annexed drawing, forming 10 part of this specification, in which—

Figure 1 is a side elevation of the vise. Fig. 2 is a top view of the same. Fig. 3 is a vertical section on line $x-x$ of Fig. 2 showing action of pawl. Fig. 4 is a section 15 on $y-y$ Figs. 1 and 2 illustrating the action of lever head.

Similar characters of reference in the several figures denote the same part of the vise.

20 The nature of my invention consists in so constructing parallel vises that their jaws shall be tightened by pressure upon a simple lever, without the agency of screw power in any form; a gathering pawl which constitutes one arm of said lever, acting upon a rack bar attached to the movable jaw, in a manner hereafter to be described, to tighten the vise; the lever being held in any given position, by means of a sliding rack, 25 so connected with a rocking head at the extremity of said lever, as to be susceptible of a lateral motion of sufficient degree to engage or disengage the securing stud at the will of the operator, in a manner hereafter to be 30 specified. In the drawing the several parts as thus represented—A stationary jaw of vise. B movable jaw—these jaws are connected by bolts a and b with the cross levers C and D, so that jaw B always moves 35 parallel to the jaw A by reason of the rise in the grooves c of the lower extremities of said cross levers. E rack bar, secured to jaw B, and passing through stationary jaw A, as shown in Fig. 3. The opening 40 through jaw A may be such as to permit in the rack bar a lateral motion sufficient to allow the holding between the jaws of an article whose opposite faces held by said jaws incline toward each other. F lever— 45 secured to one extremity of the shaft f , which is held by the lugs L, connected with jaw A by bolts e . Upon this shaft f is a pawl i , capable of engaging rack bar E under certain circumstances; said pawl con- 50 stituting the short arm of the operating

lever. H rocking head resting upon the lever F, as shown in Fig. 4, and having the sliding rack h , connected with it by the strap g as shown in same figure, causing a pressure on one side of the head H to produce a side motion of said rack h in a direction from the side of head pressed. This rack h passes through a slot in stud m of stationary jaw, and engages the inner edge of the slot when forced toward it. The 60 lower extremity of the rack h has a spring n , which when drawn into the slot of stud m , will preserve the lever F in an elevated position and lift the pawl i clear of rack bar E. 70

The operation of this vise is as follows: Before inserting the article X between the jaws, the lever F is sufficiently elevated to cause the spring n to enter the slot of stud m . The effect of this being as before stated 75 to lift pawl i into recess r and leave the rack bar E free to move. The jaw B is then drawn out, and X inserted in opening between the jaws; the jaw B at the same time closing by its weight, the cross lever maintaining it in a position parallel with A throughout its length. The hand of the operator is then placed upon the head H, causing it to drop and the pawl i to engage 80 the rack bar E. A slight pressure on the 85 said head causes the pawl i to draw powerfully on the rack bar, and compress X between the jaws. The side 1 of the head is then pressed with greater force than is bestowed on side 2, which forcing rack h 90 against the edge of its slot causes one of its teeth to engage the stud and the operation is complete, the several parts of the vise then having the positions shown in Figs. 1, 2 and 3. To release X the reverse action takes 95 place—side 2 of H is pressed upon, moving the rack h outward and disengaging its tooth from the standard. The lever F is then raised until spring n engages the slot of stud m , when the jaw B is free to move 100 outward as was first described.

The lever F may be carried to the lower portion of the vise so as to be operated by the foot, a spring being employed to carry it up when the vise is to be opened. The 105 lugs l are movable about the bolts e , the weight of the shaft and lever always keeping them in position. This construction by rendering the fulcrum movable gives the system when in operation the effect of the 110

55

toggle joint, and also insures the taking of the pawl into some tooth of the rack for holding an article of any desired size.

I do not design to restrict the operating mechanism herein described, to use upon parallel vises only, but claim the right to apply said mechanism to any other construction where it can be used with substantially the same results as herein set forth.

10 I disclaim the construction of vises where a distinct adjustment is requisite for grasping the article previous to the tightening of the jaws by lever power, as in the patented vise of Cone, and the rejected vise of Partdee, such constituting no part of my invention. But

What I do claim, and desire to secure by Letters Patent, is—

The combination of lever *F f i*, swinging lugs *l*, and rack *E*, with one jaw, *A*, fixed, 20 and one, *B*, movable in the direction of the rack, arranged and operating as specified, to grasp and tighten by one continuous movement of jaw *B*, and admitting of change of capacity without adjustment therefor. 25

In testimony whereof I have hereunto signed my name before two subscribing witnesses.

JASPER JOHNSON.
